UNITED STATES PATENT OFFICE.

FRED A. LUNDAHL, OF MOLINE, ILLINOIS.

DESIGN FOR A TOY AUTOMOBILE.

Application filed August 24, 1922. Serial No. 3,545. Term of patent 14 years.

To all whom it may concern:

Be it known that I, FRED A. LUNDAHL, a citizen of the United States, residing at Moline, in the county of Rock Island, State of Illinois, have invented a new, original, and ornamental Design for Toy Automobile, of which the following is a specification, reference being had to the accompanying drawing, forming part thereof.

The figure is a perspective view of the toy automobile showing my new design.

I claim:

The ornamental design for a toy automobile as shown.

FRED A. LUNDAHL.
